UNITED STATES PATENT OFFICE

117,746

DESIGN FOR A CONTINUOUS OUTLET STRIP

William H. Frank, Detroit, Mich.

Application July 13, 1939, Serial No. 86,044

Term of patent 14 years

To all whom it may concern:

Be it known that I, William H. Frank, a citizen of the United States and a resident of Detroit, Michigan, have invented a new, original, and ornamental Design for Continuous Outlet Strips, of which the following is a specification, reference being had therein to the accompanying drawing.

In the drawing,

Fig. 1 is a front elevation of a fragmentary portion of a continuous outlet strip showing my new design;

Fig. 2 is a rear elevation of the same;

Fig. 3 is an enlarged transverse sectional view of the strip, while

Fig. 4 is an enlarged fragmentary perspective view.

The characteristic feature of the design resides in the contrasting appearance of the dark fabric center and the bright metallic border strip especially illustrated in Fig. 4.

I claim:

The ornamental design for a continuous outlet strip, substantially as shown and described.

WILLIAM H. FRANK.
